Alexander Alloway
By H. Z. Smith, Attorney

UNITED STATES PATENT OFFICE.

ALEXANDER ALLOWAY, OF ERIE, PENNSYLVANIA, ASSIGNOR TO ERIE ART METAL COMPANY, OF MILLCREEK TOWNSHIP, ERIE COUNTY, PENNSYLVANIA, A CORPORATION OF PENNSYLVANIA.

SHEET-METAL ARTICLE.

Application filed February 7, 1920. Serial No. 357,002.

To all whom it may concern:

Be it known that I, ALEXANDER ALLOWAY, a citizen of the United States, residing at Erie, in the county of Erie and State of Pennsylvania, have invented new and useful Improvements in Sheet-Metal Articles, of which the following is a specification.

This invention relates to structural features of sheet metal articles and as exemplified are applied to a waste basket. The invention involves a corner construction in which a corner rib is secured to the sides of a corner and by means of the fold the fastening devices are covered. It also involves a construction of the top of the article, a construction of the bottom of the legs, and a construction for securing the bottom in the receptacle. Other details will appear from the specification and claims.

The invention is illustrated in the accompanying drawings as follows:—

Fig. 1 shows a side elevation of the basket.

Fig. 2 a section of a fragment of the sides and bottom with the joint in the process of formation.

Fig. 3 a fragment of a side and bottom showing the completed joint.

Fig. 4 a section on the lines 4—4 in Figs. 1 and 5.

Fig. 5 a side elevation of a leg bottom.

Fig. 6 a section on the line 6—6 in Fig. 1.

Fig. 7 a structure showing a corner rib in process of construction.

Fig. 8 shows a form of side blank.

Fig. 9 a corner construction of the top bead.

1 marks the side, 2 the bottom of the basket, 3 the top bead, 4 a corner rib terminating in legs, and 5 a leg bottom. The

sides are united by a folded joint, one side having a return bend 7 and an adjacent side having an inward bend 6 extending along the return bend and a back fold 8 arranged within the return bend.

The bottom is secured to the sides in the manner shown in Figs. 2 and 3. The sides have a return bend 9 and an inward bend 10. The bottom has a return bend 11 which is hooked into the loop formed by the return

bend 9. It will be noted that this forms a positive lock preventing the lifting of the bottom or the disengagement of the sides.

The blank of the side has a slight projection 12 at its upper end formed by a notch 13 and the edge portion 14 is turned to form a connection through the bends 6, 7 and 8. The upper edge of the side is turned over a core 15 forming a bead. The folds forming the bead have their corner or abutting edges brought into contact at 16. This is made possible particularly by the shape of the material as shown in Fig. 8 and by a stretching process after the fold is formed, that is to say, after the fold is formed the metal is forced up to the corner bringing the edges 16 into intimate contact thus making a finish.

Corner ribs are provided for the basket. These make a finish at the corner and stiffen the receptacle as a whole, improve its appearance and by extending them they form legs for the basket. The corner strip 18 has a securing edge 19 from which extends a return fold 19^a terminating in a bend or turn 22, the return bend contacting the face of the side. A securing strip 1^a is fastened to the basket sides at each side of the corner preferably by spot welding and the edges of this securing strip are provided with a return bend 1^b. In assembling the parts the return bend 1^b is not entirely closed as shown in Fig. 7. The corner strip with the securing edges 19 are placed against the return bends 1^b and the corner of the basket is placed on a horn 20 and a die 21 crushes down the corner strip closing the return bend 1^b on the securing edge 19 and closing the bend 22 giving it a completed shape as shown in Fig. 6. With a return fold covering the edge portion 19 and the outer bend 22 forming a finish along the edge of the rib, the outer bend or turn 22 should be beyond the edge of the part 19 and is slightly bent inwardly into contact with the side.

In order to finish the bottom of the legs so that they will not mar the floor or catch in rugs it is desirable to provide a larger surface than is presented by the bare end of the sheet metal. I provide, therefore, the

bottom pieces 23 which are in the form of an angle and have a bead formed over a bent wire 24, the bead being formed by a fold 25. The return plates of the metal after being 5 folded over the core 24 are brought together at 26 and inserted within the bend 22. In forming the rib, it will be understood that the portion below the sides not having the backing that the sides afford does not close 10 this space formed by the bend 22 so that this angle piece may be readily inserted.

What I claim as new is:—

1. An article of manufacture having a corner formed of sheet metal; and a corner 15 rib having its edges secured to the sides of the corner and extending outwardly from the corner and having folds extending outwardly over the portion secured to the sides.

2. An article of manufacture having a 20 corner formed of sheet metal; and a corner rib having its edges secured to the sides of the corner and extending outwardly from the corner and having folds extending outwardly over the portion secured to the sides 25 and extending beyond the edges.

3. An article of manufacture having a corner formed of sheet metal; and a corner 30 rib having its edges secured to the sides of the corner and extending outwardly from the corner and having folds extending outwardly over the portion secured to the sides and extending beyond the edges and into contact with the sides.

4. An article of manufacture having a 35 corner formed of sheet metal; and a corner rib having its edges secured to the sides of the corner and extending outwardly from the corner and having folds extending outwardly over the portion secured to the sides, the rib being spaced from the corner at 40 points nearer the corner than the edges.

5. An article of manufacture having a 45 corner formed of sheet metal; a corner securing strip around the corner and secured to the metal thereof, said securing strip having return bends at its edges; and a corner rib having its edges formed with an outward bend extending into a return bend of the securing strip and having an outwardly extending fold. 50

6. An article of manufacture having a corner formed of sheet metal; a corner securing strip around the corner and secured to the metal thereof, said securing strip 55 having return bends at its edges; and a corner rib having its edges formed with an outward bend extending into a return bend of the securing strip and having an outwardly extending fold extending over the 60 return bend of the securing strip.

7. An article of manufacture having a corner formed of sheet metal; a corner securing strip around the corner and secured to the metal thereof, said securing strip 65 having return bends at its edges; and a

corner rib having its edges formed with an outward bend extending into a return bend of the securing strip and having an outwardly extending fold extending over the return bend of the securing strip and into contact with the sides. 70

8. A basket formed of sheet metal and having sides, the connection between the sides forming a corner formed of sheet metal; and a corner rib having its edges secured to the sides of the corner and extending outwardly from the corner and having folds extending outwardly over the portion secured to the sides. 75

9. A basket formed of sheet metal and having sides, the connection between the sides forming a corner formed of sheet metal; and a corner rib having its edges secured to the sides of the corner and extending outwardly from the corner and having folds extending outwardly over the portion secured to the sides, said rib extending below the sides to form legs for the basket. 80

10. A basket formed of sheet metal and having sides, the connection between the sides forming a corner formed of sheet metal; and a corner rib having its edges secured to the sides of the corner and extending outwardly from the corner and having folds extending outwardly over the portion secured to the sides and extending beyond the edges, said rib extending below the sides and forming legs for the basket. 85

11. A basket formed of sheet metal and having sides, the connection between the 90 sides forming a corner formed of sheet metal; and a corner rib having its edges secured to the sides of the corner and extending outwardly from the corner and having folds extending outwardly over the portion secured to the sides and extending beyond the edges and into contact with the sides, said ribs extending below the sides and forming legs for the basket. 95

12. A basket formed of sheet metal and having a corner at the union of its sides; a securing strip extending around the corner and secured to the sides thereof, said securing strip having return bends at its edges; and a corner rib having its edges formed with an outward bend extending into a return bend of the securing strip and having an outwardly extending fold extending over the return bend of the securing strip. 110

13. A basket formed of sheet metal and having sides, the connection between the sides forming a corner formed of sheet metal; a corner rib having its edges secured to the sides of the corner and extending outwardly from the corner and having folds extending outwardly over the portion secured to the sides, the rib being spaced from the corner at points nearer the corner than the edges; and a beaded angle piece inserted into the bottom of the leg, the fold 120

on the leg covering the edges of the angle piece.

14. A receptacle formed of sheet metal having corners and an outwardly extending beaded top edge, said bead having a wire core and the metal of the edge being folded over the core, the fold of each side abutting

through the outer portion of the fold with the edges of the fold on the adjoining sides. 10

In testimony whereof I have hereunto set my hand.

ALEXANDER ALLOWAY.
